UNITED STATES PATENT OFFICE.

WILBUR G. LAIRD, OF NEW YORK, N. Y., ASSIGNOR TO HENRY L. DOHERTY, OF NEW YORK, N. Y.

COKE-DISCHARGING APPARATUS.

Application filed November 3, 1920. Serial No. 421,441.

To all whom it may concern:

Be it known that I, WILBUR G. LAIRD, a citizen of the United States of America, residing at New York city, in the county of 5 New York, State of New York, have invented certain new and useful Improvements in Coke-Discharging Apparatus; and I do hereby declare the following to be a full, clear, and exact description of the invention, 10 such as will enable others skilled in the art to which it appertains to make and use the same.

This invention relates to a coke discharging apparatus for coal carbonizing shaft 15 furnaces.

The subject matter of the present case constitutes a division of my former application for "coal carbonizing furnaces," Serial No. 253,046, filed September 2nd, 1918.

20 In shaft furnaces of the type shown in the above application, the coal to be carbonized or distilled by a continuous operation is supported in a vertical column and moves slowly downwardly through the furnace 25 while passing through a series of heat treatment zones. The entire column of coke and partly carbonized coal is supported at the bottom of the furnace and a portion of the coke may be continuously removed from the 30 bottom, thereby permitting the entire column of coking material to gradually work downwardly through the furnace at any desired rate of speed. The gradual and regular removal of the coke from the bottom 35 of the furnace is rendered difficult by the great weight of the material and the tendency of the coke to pack into compact masses which are difficult to break and which obstruct the insertion or the movement of 40 moving elements through the body of coke. The coke discharging apparatus should, moreover, be so arranged that it will permit a uniform distribution and a free upward 45 passage of gases which are introduced into the furnace to act as a heat transferring medium.

The primary object of the present invention is to provide a discharging apparatus for shaft furnaces capable of supporting a column of fuel and for removing fuel from the bottom of the column at any desired rate.

It is essential, in order to obtain the best results, that the carbonizing material should move at substantially the same rate through-

out the entire cross-section of the furnace so 55 that every portion of the coal should receive the same treatment in each of the temperature zones. A uniform condition and porosity in the carbonizing material is also produced by the uniform movement of the 60 carbonizing column, thereby maintaining a better distribution and more uniform flow of treating gases and products of decomposition upwardly through the carbonizing column. The fuel may be removed intermittently or continuously, but in either case a 65 uniform condition of the fuel and treating gases in the shaft is promoted by the removal of coke at a uniform rate throughout the entire cross-section of the bottom of the 70 column.

A further object of the invention is therefore to provide a discharging apparatus for shaft furnaces by which the fuel is removed uniformly throughout the cross-sectional 75 area at the bottom of the fuel column.

A further object of the invention is to provide a fuel discharging device located at the bottom of a column of fuel, arranged to allow heat transferring gas to enter the 80 fuel column freely throughout the entire cross-sectional area of said column.

With these and other objects in view, the invention consists in the apparatus described in the following specification and defined in the claims.

The various features of the invention are shown in the accompanying drawings, in which:

Fig. 1 is a vertical sectional view of a 90 coal carbonizing shaft furnace provided with a fuel discharging device embodying a preferred form of the invention;

Fig. 2 is a horizontal sectional view of the furnace on the line 2—2 of Fig. 1; and

Fig. 3 is a plan view of a coke discharging apparatus.

The furnace shown in the accompanying drawings comprises an upright cylindrical shell 10 into which coal to be carbonized is 100 fed through a valve device 12 in the top of the furnace. The coal moves downwardly through the furnace and passes through zones of constantly increasing temperature into a high temperature or distilling zone 14 enclosed within a refractory lining 16 in the furnace shell 10. The coke formed in the zone 14 passes downwardly through tem-

perature zones which become continually cooler towards the bottom and is removed by a discharging apparatus 18. The coke discharged by the apparatus 18 falls into a 5 hopper 20 which is closed gas tight by a door 22. From the hopper 20, the coke is discharged into a second hopper 24 from which it is delivered upon opening a door 26 in the bottom of the hopper. Steam or other 10 gaseous heat transferring medium for controlling the temperatures in the fuel column and the coal carbonization, enters the furnace through an inlet 28 in the shell 10 adjacent the coke discharging device 18 and 15 passes through the coke discharging device and upwardly through the downwardly moving column of coke. From the upper part of the furnace the gas formed by the carbonization of the coal and the gas introduced 20 as a heat transferring medium leave through an outlet 30.

The coke discharging device 18 serves to support the column of coal and coke in the furnace and to permit removal of coke from 25 the bottom of the column as desired. The column of coke and coal is supported directly on an annular supporting plate 32 and a deflecting cone 34 positioned above the center of the annular plate 32. An annular 30 space or opening 36 through which coke passes to the plate 32 is formed above the plate between the outer edge of the cone 34 and an apron 38 extending downwardly from the refractory lining 16 of the furnace. 35 The plate 32 is wider than the opening 36 and extends inwardly under the cone 34 and outwardly below the apron 38 to such a distance that the coke passing downwardly through the opening 36 and spreading out 40 on the plate 32 will not flow unaided by other means over the edges of the plate and will, therefore, support the column of coke above the opening 36. The coke reaching the plate 32 is removed by a discharging 45 scraper and a corresponding quantity of coke passes downwardly through the opening 36, thereby permitting the entire column of coke and coal to sink downwardly through the furnace.

50 The coke is discharged from the plate 32 by the movement over the plate of a scraping ring 40 having an upright coke engaging flange 42. The ring is given a gyratory movement over an annular wear plate 44 resting on the plate 32, in such a manner 55 that the outer edge of the ring rolls tangent to the outer edge of the wear plate and the inner edge of the ring tangent to the inner edge of the wear plate. The points of tangency of the inner and outer edges are 60 always diametrically opposite and travel around the inner and outer edges of the wear plate. During each gyration of the ring 65 40 over the wear plate it therefore reciprocates radially over every part of the breadth

of the plate and by means of the upright flange 42 brushes a uniform amount of coke over the edges of the supporting plate 32. A uniform overflow of coke over the entire periphery of the inner and outer edges of 70 the supporting plate 32 is thereby produced during each gyration and an equivalent quantity of coke is permitted to pass uniformly downwardly through the opening 36. The wear on the ring 40 due to its travel 75 over the wear plate is taken up by an annular wear ring or shoe 46 attached to the bottom of the ring.

A gyratory movement is imparted to the ring 40 by means of two pistons 48 and 50 80 reciprocating in cylinders 52 and 54, respectively, mounted on the shell 10 of the generator. The movement of the pistons 48 and 50 is transmitted by means of piston rods 56 and 58 passing through stuffing 85 boxes on the cylinders 52 and 54 and on the generator shell 10 to connecting rods 60 and 62. The connecting rods 60 and 62 are pivotally connected to a pivot pin 64 to which the ring 40 is rigidly fastened by 90 means of spokes 66.

The movement of one of the pistons 48 or 50 precedes the other by a distance corresponding to one-quarter of a revolution of 95 the pivot pin 64, so that when harmonic motion is given to the pistons, the pivot 64 will travel in a circle concentric with the centre of the plate 32.

Using the above described apparatus, the coke passing downwardly through the furnace is deflected through the opening 36 by the cone 34 and is discharged uniformly from every part of the annular opening 36 by the ring 40. To break up any large lumps of coke passing through the opening 36, a series of webs or plates 68 extend radially inwardly from the wall 10 of the furnace. As the ring 40 is brought towards the plates 68 any particles caught between the ring and the plates will be crushed to a 110 smaller size before being swept over the edge of the plate.

The column of fuel is supported by the discharging device and heat transferring gases from the inlet pipe 28 are permitted 115 to enter the bottom of the column of fuel uniformly throughout the area of said column. To facilitate the uniform distribution of the heat transferring gases, the apron 38 and the cone 34 are provided with a number of perforations. The gases are therefore free to enter throughout the periphery of the apron 38 and throughout the area of the cone 34 and to enter the opening 36 through the spaces between the lower edges 120 of the cone 34 and apron 38 and the top of the supporting plate 32. By the agitation and discharging of the coke with the movement of the ring 40 and flange 42 and the crushing of large lumps between the flange 125 130

42 and the plates 68, the bottom of the column of fuel is maintained in an open and porous condition, thus providing a large number of openings throughout the area of 5 the column and insuring a uniform resistance to the entrance of gas throughout the area of the column.

The cone 34 is supported by means of three radial plates or beams 70 which extend 10 from the centre of the cone outwardly to the apron 38. The apron is supported by the plates 68 which are, in turn, supported by columns or pillars 72 arranged to carry the entire weight of the furnace. The annular plate 32 rests on a series of I-beams 15 74 which are connected adjacent the plates 68.

In the above described coke removing apparatus, practically none of the weight of 20 the column of coke rests on moving elements of the coke discharging device and consequently very little resistance is offered to the removal of coke from the bottom of the column. The removal of coke is moreover 25 substantially uniform throughout the entire cross-section of the column. The agitation of the bottom of the coke serves to break up any air channels that may be formed in the column and to insure an even distribution of 30 gas throughout the column.

In the above specification the plate 32 has been shown as being circular in form, and described as an annular plate or annulus. It is not essential, however, that the plate be 35 circular and the word "annular" when used in the above specification and in the following claims, is intended to include all forms of plates having an opening in their centre.

Having described the preferred form of 40 the invention, what is claimed as new is:

1. A coke discharging device for shaft furnaces which comprises a plurality of supporting surfaces in different vertical planes, the outer and inner edges of consecutive surfaces overlapping, an annular ring on the lower surface, and means for giving said ring a reciprocatory motion.

2. A coke discharging device for shaft furnaces which comprises a deflecting cone positioned in the centre of the shaft, an annular supporting plate positioned below, and having its outer edge extending under the inner edge of said furnace wall, and its inner edge extending under said deflecting cone, a movable ring on said supporting plate and means for giving said ring a gyratory motion.

3. A coke discharging device for shaft furnaces, which comprises a deflecting cone positioned in the centre of the shaft, an annular supporting plate positioned below and having its outer edge extending beneath the inner wall of said furnace, and its inner edge extending beneath said cone, a movable ring resting on said supporting plate, a pivot in 55 the centre of said ring, rods extending from

said ring to said pivot, connecting rods pivoted to said pivot and extending at an angle to each other, and power operated pistons outside of said furnace to which said connecting rods are attached.

4. A coke discharging device for shaft furnaces which comprises a plurality of supporting surfaces, in different vertical planes, the edges of consecutive surfaces overlapping a distance sufficient to bring the lower edge 70 of the supported material within the edges of the lower supporting surfaces, and a flanged ring for moving said material over the edges of the lower supporting surfaces.

5. A coke discharging device for shaft furnaces which comprises a plurality of supporting surfaces placed at different vertical planes, the edges of consecutive surfaces overlapping a distance sufficient to bring the lower edge of the supported material within the edges of the lower supporting surface, a central discharge opening in the lower supporting surface, means for moving said material over the central and outer edges of the lower supporting surface, and means co-acting with said moving means for breaking up large masses of the material to be removed.

6. A coke discharging device for shaft furnaces which comprises a central perforated deflecting cone in said furnace, an annular supporting plate spaced below said cone and having its inner and outer edges extending beneath said cone and the inner wall of said furnace respectively, an annular ring resting on said supporting plate, a series of vertical radial plates extending downwardly from the furnace wall, and means for giving said ring a gyratory motion over said supporting plate.

7. A coke discharging device for shaft furnaces which comprises a central perforated deflecting cone in said furnace, an annular supporting plate spaced below said cone and having its inner and outer edges extending beneath said cone and the inner wall of the furnace respectively, an annular ring resting on said supporting plate, a series of vertical radial plates extending downwardly from said inner furnace wall, cylinders mounted on said furnace, power operated pistons within said cylinders, and means connecting said pistons to said ring.

8. A fuel support for shaft furnaces arranged to permit gases to freely enter a column of fuel, which comprises a porous apron extending downwardly from within the inner wall of said furnace, a cone positioned within and spaced from said apron, and an annular plate positioned below and spaced from said cone and said apron and means to introduce gas below the said plate and through the said cone and apron.

9. A coal carbonizing furnace having in

- combination, a vertical gas-tight shell, a central deflector mounted near the bottom of said shell, an apron surrounding and spaced from said deflector to leave a discharge opening for coke and spaced from the inner wall of said shell to provide a gas passage, an annular plate supported below said discharge opening, having a discharge passage through the central opening thereof, 5 a scraper on said plate, and means to impart a gyratory movement to said scraper to reciprocate the scraper across each part of the central opening of said plate to discharge material therethrough.
- 10 10. A coal carbonizing furnace having in combination a gas-tight shell, a support for a column of fuel in said shell comprising an annular plate having its outer edge spaced from the inner face of the shell and 20 arranged to receive fuel discharged from
- 25 said fuel column, a scraper on said plate, and a pair of separately operated driving means mounted at an angle to one another and connected with said scraper to simultaneously operate on said scraper for imparting a discharging movement thereto.
11. A coal carbonizing furnace having in combination a gas-tight shell, a support for a column of fuel within said shell comprising an annular plate having its outer edge 30 spaced from the inner face of the shell and arranged to receive fuel from said fuel column, a scraper on said plate, and means for operating said scraper comprising pistons mounted on said shell at right angles to 35 each other, and means for connecting said pistons to a common point on the scraper.

In testimony whereof I affix my signature.

WILBUR G. LAIRD.
